UNITED STATES PATENT OFFICE.

ALEX BERNSTEIN, OF BOSTON, MASSACHUSETTS.

ELECTRIC-CURRENT METER.

SPECIFICATION forming part of Letters Patent No. 269,559, dated December 26, 1882.

Application filed October 4, 1882. (No model.)

To all whom it may concern:

Be it known that I, ALEX BERNSTEIN, of Boston, in the county of Suffolk and State of Massachusetts, have invented certain new and useful Improvements in Current-Meters, of which the following is a specification.

This invention relates to an improved automatic current-meter, whereby the quantity of current used in the main line or any branch thereof can be ascertained and conveniently read off at any time in a correct and reliable manner; and the invention consists of a fulcrumed scale-beam, which carries at one end a traversing and counterbalanced registering device and at the other end a coil into which is placed a soft-iron core connected by a rod to the register. Below the arm carrying the registering device is suspended a coil, which is surrounded by a second coil of larger diameter, the latter being constantly traversed by the main or branch current, while the smaller coil and the coil on the beam are traversed at stated periods by an auxiliary current of constant and known strength. The registering device and scale-beam are retained in a position of rest—to wit, a horizontal position—by means of a spring-catch and fixed rack-bar, which latter is arranged above the registering device, as will all appear more fully hereinafter and finally be pointed out in the claims.

In the accompanying drawings, Figure 1 represents a diagram showing the connection of the different branch circuits with the main circuit and with the auxiliary circuit, that is used for working all the current-meters at stated intervals of time. Fig. 2 is a side elevation of my improved current-meter, partly in section. Fig. 3 is a plan view of the same, and Fig. 4 a side view of the registering device drawn on a larger scale.

Similar letters of reference represent corresponding parts.

For the purpose of measuring the current supplied to the main or branch circuits an auxiliary current is employed, the strength of which is known and kept constant. This current is thrown through all the current-meters at certain stated periods of time—say every five minutes—and thereby the main current measured by its action upon the auxiliary current and the measurement mechanically indicated

upon the current-meters. Each current-meter is constructed of a vertical standard, A, which supports an oscillating beam, B, turning on knife-edged trunnions. To one arm of the beam B is applied a traversing registering device, C, to which is connected a weight, a, by a wire string, b, passing over the pulley b' at the outer end of the arm. The registering device C is also connected by a rod, d, with a soft-iron core, D, which is guided in any suitable manner into a coil, D', attached to the opposite arm of the scale-beam B.

From that arm of the scale-beam which carries the registering device is suspended a coil, E, which is inserted or dipped into a coil, E', of larger diameter, the latter coil being traversed by the current of the main circuit. The interior coil, E, and the coil D' at the outer end of the scale-beam form part of the auxiliary circuit, through which the current is passed at certain fixed intervals of time by a battery and a clock and suitable circuit-closing devices at the central station. As soon as the auxiliary current is thrown into the line 75 the inside coil, E, will be drawn down into the outside coil, E', and thereby the scale-beam B lowered at that side from which the smaller coil is suspended. The auxiliary current passes at the same time through the fixed coil D' at 80 the opposite end of the scale-beam and causes the iron core to be drawn into the coil, whereby the registering device is moved forward upon the beam until equilibrium is again established and the beam returned to horizontal position.

The way or distance which has to be travelled by the registering device in order to establish equilibrium of the parts is measured by the following formula: Let s be the distance the register has to move; I , the strength of the main current to be measured; i , the strength of the auxiliary current; C , a constant of the instrument dependent on the length of wire in both coils and other details. Then 95 s is equal to $I \times i \times C$. As i is a current of constant and known strength, then s is proportional to I , or, in other words, the distance through which the register moves in order to establish equilibrium corresponds directly to 100 the strength of the current to be measured.

In order to indicate by mechanical means

the distance through which the register moves, the arm of the scale-beam B which carries the register is made in the shape of a rack, and the registering device provided with a small pinion, which gears with the rack and transmits its motion by a train of gear-wheels to index-hands moving over dial-plates in the usual manner. The hands of the dial can only be moved when the registering device moves 5 in one direction, they being not moved when the registering device moves in the opposite direction, so that the return motion of the register has no effect upon the hands, as is well known in registering devices of this class. In 10 this way the strength of the main current is indicated by means of the auxiliary current every five minutes, or at longer or shorter intervals of time, as desired, and thereby the amount of current passing over the main line 15 or in any branch thereof to which the meter is applied accurately determined.

In connection with the registering device of the current-meter, and above the same, is arranged a fixed horizontal rack-bar, F, which 20 is engaged by means of a spring-catch, F', applied to the register. As soon as the auxiliary current is made to pass through the coils E and D' the beam is deflected at the left end, and the iron core D will be drawn inside of the 25 coil D' at the right end. As the register is drawn toward the right by the action of the coil on the iron core until equilibrium is again established, the beam assumes again a horizontal position, and no further motion of the register can take place, as the spring-catch of the 30 same engages the fixed rack-bar. According to the explanation given, the distance which the sliding register was compelled to move in order to establish equilibrium of the beam corresponds directly to the strength of the main 35 current to be measured. After this action has taken place the auxiliary current is discontinued and the small counter-weight on the left side of the beam brings the sliding register 40 back to its original position, where it is arrested by the stop d' on the rod d coming in contact with the slotted standard f, through which said rod slides. The stop d may consist 45 of a collar loose on the rod, and provided with

a set-screw for holding it in place when adjusted into the proper position.

The current is furnished in the usual manner by a dynamo-electric machine and distributed from the main line over the branch lines, in each of which any number of lamps may be placed, as indicated in Fig. 1. A battery at the central station supplies the auxiliary current for the auxiliary line.

In place of a battery, a small magneto-electric machine may be used. A clock serves to close the current of this battery every five minutes by means of suitable circuit-closing devices, the current being interrupted again after it has acted a certain time—say two or three minutes. A galvanometer and resistance-coils may be used in order to measure and keep constant the strength of the auxiliary current.

Having thus described my invention, I claim as new and desire to secure by Letters Patent—

1. A current-meter composed of a scale-beam, of a movable and counterbalanced registering device at one end of the beam and of a fixed coil and a sliding iron core connected to the registering device at the other end of the beam, of a coil suspended below the end of the beam, carrying the register and placed in an auxiliary circuit with the coil at the other end of the beam, and of a fixed coil of larger diameter and surrounding the suspended coil, and being placed into the main circuit, substantially as set forth.

2. The combination of a scale-beam carrying a movable and counterbalanced registering device upon one arm, a coil and sliding core upon the other arm, a coil suspended from the arm carrying the register, a fixed coil surrounding the suspended coil, and a suitable stop mechanism, whereby the register is stopped when the equilibrium of the parts takes place, substantially as and for the purpose set forth.

In testimony that I claim the foregoing as my invention I have signed my name in presence of two subscribing witnesses.

ALEX BERNSTEIN.
